UNITED STATES PATENT OFFICE

132,522

DESIGN FOR AN URN

Edwin W. Fuerst and Charles W. Sawyer, Toledo,
Ohio, assignors to Libbey Glass Company,
Toledo, Ohio, a corporation of Ohio

Application September 25, 1941, Serial No. 103,484

Term of patent 7 years

To all whom it may concern:

Be it known that we, Edwin W. Fuerst and Charles W. Sawyer, citizens of the United States, residing at Toledo, in the county of Lucas and State of Ohio, have invented a new, original, and ornamental Design for an Urn, of which the following is a specification, reference being had to the accompanying drawing, forming a part thereof.

In the drawing:

Fig. 1 is a side elevational view of an urn showing my new design.

Fig. 2 is a top plan view thereof.

We claim:

The ornamental design for an urn, substantially as shown.

EDWIN W. FUERST.
CHARLES W. SAWYER.
